(57) **CLAIM**

The ornamental design for a shoe, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front and left side perspective view of a shoe, showing a new design in accordance with the present invention;

FIG. 2 is right side view thereof;

FIG. 3 is left side view thereof;

FIG. 4 is front view thereof;

FIG. 5 is a bottom and right side perspective view thereof;

FIG. 6 is a top view thereof; and,

FIG. 7 is a rear view thereof.

1 Claim, 7 Drawing Sheets
